(57) CLAIM

The ornamental design for a ceiling fan, as shown and described.

DESCRIPTION

FIG. 1 is a perspective view of a ceiling fan in accordance with my design, wherein a first side fan and a second side fan are in a first position;

FIG. 2 is a side elevation view of the ceiling fan in accordance with my design, wherein the first side fan and the second side fan are in a second position;

FIG. 3 is a side elevation view of the ceiling fan in accordance with my design, wherein the first side fan and the second side fan are in the first position;

FIG. 4 is a side elevation view of the ceiling fan in accordance with my design, wherein the first side fan is in a third position, and the second side fan is in the first position;

FIG. 5 is a bottom plan view of the ceiling fan in accordance with my design, wherein the first side fan and the second side fan are in the first position;

FIG. 6 is a top plan view of the ceiling fan in accordance with my design, wherein the first side fan and the second side fan are in the first position;

FIG. 7 is a front elevation view of the ceiling fan in accordance with my design, wherein the first side fan is in the first position; and,

FIG. 8 is a back elevation view of the ceiling fan in accordance with my design, wherein the second side fan is in the third position.

The broken-line disclosure of elements is understood to represent portions of the article in which the design is embodied, but which form no part of the claimed design. The lighter and closely spaced lines in the drawings are surface shading and are not surface ornamentation.
